COMBINED DATA KEYBOARD ENTRY AND DISPLAY UNIT

Gerald M. Adams, Fayetteville, and James H. Frakes, Jr.,
Manlius, N.Y., assignors to SCM Corporation, New
York, N.Y.

Filed May 15, 1970, Ser. No. 22,992

Term of patent 14 years

Int. Cl. D14—02

U.S. Cl. D26—5

FIG. 1**FIG. 2**

FIG. 1 is a front perspective view of a combined data keyboard entry and display unit showing our new design; FIG. 2 is a top plan view thereof; FIG. 3 is a left elevational view thereof; FIG. 4 is a front elevational view thereof; FIG. 5 is a right elevational view thereof; and FIG. 6 is a rear elevational view thereof.

We claim:

The ornamental design for a combined data keyboard entry and display unit, substantially as shown.
